ABSTRACT OF THE DISCLOSURE

An ignition device for oil burners including a body of thermoplastic or thermosetting material carrying the two electrodes for providing an ignition spark adjacent the nozzle of the oil burner. This body is formed with an aperture receiving a component of the oil burner, such as, for example, a nozzle adapter. The external surface of the adapter and the aperture in the body are so formed as to prevent relative angular displacement of the body with respect to the oil burner component, while providing for axial movement of the body relative to the component of the oil burner. Pressure exerting means are provided for assuring a tight conforming fit between the body and the component part of the oil burner, preventing relative angular displacement of these two parts.

This invention relates to ignition devices for oil burners and, more particularly, to a novel and improved holder for the sparking electrodes used to ignite oil sprayed from an oil burner nozzle.

It is known to ignite oil burners, for example, those burning residual oils, by a flashing spark at a voltage of about 8,000 to 15,000 volts between electrodes provided for this purpose. These electrodes are mounted in a member called an "electrode holder," fixed on an appropriate element of the burner. For example, such element could be the nozzle adapter of the burner. A nozzle adapter is generally machined from brass and is threaded or soldered to the end of the oil supply tube and carries, at its free end, an oil atomizing nozzle.

In known constructions, these electrode holders comprise a metal body fixed on the adapter, and formed with two parallel bores receiving the isolating shields, of ceramic material, in which are mounted the hollow pins of soft steel carrying the electrodes proper. The electrodes are generally formed of silicon steel wire.

The known arrangement has various disadvantages. Above all, it is expensive as it is composed of a number of distinct parts of different materials which must be secured to each other by suitable securing means such as screws, threaded joints, or the like, to provide an assembled unit. On the other hand, the assembly thus constructed is fragile by reason of the presence of sleeves of ceramic material.

An object of the present invention is to avoid the disadvantages of prior art electrode holders.

Another object of the invention is to provide an electrode holder comprising a body molded from insulating material of either a thermoplastic or thermosetting nature and preferably possessing a certain elasticity.

1
2
A further object of the invention is to provide an electrode holder of the type just-mentioned which is designed to be fixed on an appropriate support element, such as the nozzle adapter or the oil supply tube of an oil burner, and to mount the known type of sleeves carrying the electrodes proper.

2
Yet another object of the invention is to provide an electrode holder of the type mentioned in which fixing of the electrode holder on its support is assured by the pressure produced by elastic deformation of the electrode holder body resulting from its mounting on the support element.

3
A further object of the invention is to provide an electrode holder in which the elastic pressure of the body of the holder on the support element is sufficient to retain a desired longitudinal position while permitting displacement of the body slidably along its support element by the application of a suitable force.

4
Still another object of the invention is to provide an electrode holder of the type mentioned and which has a conforming fit with the support surface which is formed to prevent rotation of the electrode holder body on its support.

5
Still a further object of the invention is to provide an electrode holder of the type mentioned in which the body of the holder is mounted on its support with the help of a groove cooperating with a conforming surface of the support element and having a small play therewith, the elastic pressure being produced by a projection oriented to press toward the interior of the groove upon engagement of the body of the electrode holder on its support element.

6
Still another object of the invention is to provide such an arrangement in which the projection is preceded by a ramp facilitating engagement of the electrode of the electrode holder with its support element and assuring a progressively increasing elastic pressure.

7
A further object of the invention is to provide an electrode holder of the type mentioned in which the sleeves carrying the electrodes proper are imbedded in the body of the electrode holder during molding of the body.

8
Yet another object of the invention is to provide an electrode holder of the type mentioned and which is formed as a one-piece unit integral with the nozzle adapter.

9
For an understanding of the principles of the invention, reference is made to the following description of typical embodiments thereof as illustrated in the accompanying drawings.

10
In the drawings:

11
FIG. 1 is a front elevation view of an electrode holder embodying the invention;

12
FIG. 2 is a side elevation view of the electrode holder;

13
FIG. 3 is a side elevation view of the electrode holder of FIGS. 1 and 2 as mounted on a nozzle adapter of an oil burner; and

14
FIG. 4 is a view similar to FIG. 3 but showing a variation in which the electrode holder is mounted on the oil supply tube of the oil burner.

15
In the embodiment of the invention shown in FIGS. 1 and 3, the body of the electrode holder 1 is molded from

a thermoplastic or thermosetting dielectric synthetic resin material, for example, that known under the name of "Rilsan." The body 1 mounts two cylindrical electrodes 2 of soft steel. Each electrode carries coaxially thereof, at one of its extremities, a silicon steel pin 3 having a diameter less than the electrode 2. The exterior parts 4 of the pins 3 are finally bent manually to regulate the spacing and the positioning of the electrode points 5. These pins extend through an axial cylindrical passage in the associated electrode 2 and are maintained therein by the pressure due to preliminary deformation of the pins to provide projections in a zone thereof which is at the longitudinal center of the passage when the pins are inserted therein. This deformation deforms the soft steel of the electrode sleeve by metal flow to form two diametrically opposite projections 6 which form lateral projections engaging in the electrode holder.

A thread 7, either S.I. or I.S.O., is formed on the other end of each electrode 2 and provides for fixing thereto a connection (not shown) for feeding the high voltage electric current, produced by an ignition transformer, to the electrodes.

The process of producing each electrode is known per se. The lateral projections 6 extending diametrically of each electrode 2 prevent rotational or translatory movement of the latter when the plastic material of the body of the electrode holder 1 is poured, and during its hardening, around the electrodes 2 which have been previously positioned in a suitable mold.

The length and the position of the electrodes is a function of the usual regulation of the spark ignition, under high voltage, of an atomized oil jet discharged from the nozzle.

All modifications of dimensions, of position, and of spacing of electrodes are possible and are within the scope of the invention.

The positioning of the thus formed electrode holder on the nozzle adapter A is then effected, the adapter A being of a known type and having the dimensions and the form required by the usual international specifications.

The adapter has a cylindrical external surface along part of its length, usually formed by machining a bar of polygonal, such as hexagonal, cross section. The cylindrical part represents about two-thirds of the total length of the adapter, and the rest of the external surface of the adapter is constituted by the six side faces of the bar.

The electrode holder 1 is formed, along an axis parallel to the axes of electrodes 2, with a hexagonal aperture 8 whose dimensions are slightly in excess of the dimensions of the hexagonal part of the nozzle adapter A. The assembly tolerances provided to the order of tenths of a millimeter are compatible with a correct fixing of the two pieces one on the other. The coincidence of the hexagonal bore 8 with the hexagonal exterior surface of adapter A provides for positioning of the electrode holder in a fixed radial relation on the adapter A, preventing rotation of the electrode holder.

In order to provide an axially fixed positioning of the electrode holder 1 on the nozzle adapter, the interior surface 9 of the hexagonal bore 8 is formed, along an axis tangent to the middle of this face and parallel to the axes of the electrodes, with a projection 10 whose right section is approximately that of a semi-circle. This bulge or projection 10 is formed by molding at the same time as the electrode holder is molded.

In order to permit the mounting of the electrode holder 1 on the hexagonal part of adapter A, the projection 10 includes, at one of its ends, an inclined plane 11. The frictional engagement of the holder on the adapter is effected in the following manner. The projection 10, upon mounting of the electrode holder on the adapter, deforms the lateral face 9 of bore 8 from which it projects, and thus induces a lateral pressure on the other faces of the hexagonal bore 8, such as the faces 12 and 13, against the corresponding surfaces of adapter A. The elasticity of

the plastic material used, and the assembly tolerances, permit the necessary slight deformations to effect a frictional drag between the two pieces, without interfering with the sliding friction, easily performed by hand. The height of the projection 10 will be determined to provide the correct pressure between the two pieces.

In the modification shown in FIG. 4, the electrode holder can be fixed in the same manner on the oil feed tube rather than on the nozzle adapter. Hexagonal bore 8, in FIG. 4, is replaced by a cylindrical bore 14 having a diameter corresponding to the diameter of the oil feed tube 15. Positioning is effected by virtue of sliding the two parts relatively, radially and axially of the tube, and the fixed position is set by means of a set screw or the like 16.

Electrode holders in accordance with the invention have many advantages in comparison with known electrode holders. Thus, they are less expensive because the number of parts has been reduced to the body of dielectric material and the electrodes. The electrodes are fixed in the body of the holder during molding of the latter and without the necessity of providing the separate means for holding the electrodes in the body. The fixed positioning of the body of the electrode holder on its support element is automatically assured by elastic deformation occurring during mounting of the body of its support element without the necessity for using separate fixing means such as screws or similar elements. Furthermore, the electrode holder is easily adjusted by sliding, on its support element, in addition to the electrode holder having a strong construction. The electrode holder is easy to fabricate inasmuch as it is molded, and it presents a reduced incumbrance.

It should be especially noted that the electrode holder can be manufactured as a single piece with the adapter and secured with the latter to the oil feed tube.

While specific embodiments of the invention have been shown and described in detail to illustrate the application of the principles of the invention, it will be understood that the invention may be embodied otherwise without departing from such principles.

What is claimed is:

1. An electrode assembly, for the high voltage spark ignition of an oil burner having projecting ignition electrodes and including, as components, an oil supply tube and a nozzle adapter mounted on the supply tube, said electrode assembly comprising a relatively elastic molded body of dielectric synthetic resin material constructed to receive sleeves carrying the projecting electrodes; said body being constructed for fixed mounting on a component of the oil burner through its inherent elasticity; said body being formed with an aperture having a contour conforming to that of the component on which it is mounted, in a manner such as to restrain relative angular displacement of said body on its mounting component; said body having tightening means thereon projecting into the interior of said aperture to engage the body mounting component to tighten the body on its mounting component by elastic deformation of the body, and providing for sliding of said body on its support component in a direction extending axially of the latter.

2. An electrode assembly, as claimed in claim 1, in which said elasticity provides a pressure, when said body is mounted on its component, maintaining said body substantially fixed in position against angular displacement on its mounting component.

3. An electrode assembly, as claimed in claim 2, in which the elastic pressure exerted between said body and its component has a value sufficient to retain the body fixed longitudinally on its component while providing for longitudinal displacement of the body by sliding along its mounting component under a force of a pre-selected value.

4. An electrode assembly, as claimed in claim 2, in which the elastic pressure is produced by a pressure projection integral with said body and extending toward the

interior of said aperture, upon engagement of said body with its support component.

5. An electrode assembly, as claimed in claim 4, including a ramp sloping away from said projection and facilitating engagement of said body on its support component while assuring a progressively increasing pressure.

6. An electrode assembly, as claimed in claim 1, in which the material of said body is selected from the class consisting of thermoplastic and thermosetting synthetic resins possessing elasticity in the formed state.

7. An electrode assembly, as claimed in claim 1, in which the component mounting said body has a polygonal cross section, and said aperture has a polygonal cross section conforming to that of the mounting component.
